UNITED STATES PATENT OFFICE

2,371,934

HOLDING JIG

George St. Marie, South Dartmouth, Mass.

Application March 2, 1944, Serial No. 524,747

1 Claim. (Cl. 82—40)

The present invention relates to new and useful improvements in holding jigs, and has for its primary object to provide, in a manner as hereinafter set forth, novel means for firmly securing taps, reamers and other tools in position on a grinding or turning machine without the usual dogs.

Another very important object of the invention is to provide a jig of the aforementioned character which will permit the tool to be ground or turned to be readily reversed to facilitate operation on the shank thereof after the body of said tool has been treated.

Still another very important object of the invention is to provide a holding jig of the character prescribed which may be readily adjusted to accommodate different lengths of tools to be ground or turned.

Other objects of the invention are to provide a holding jig of the character set forth which will be comparatively simple in construction, strong, durable, highly efficient and reliable in use, compact and which may be manufactured at low cost.

All of the foregoing, and still further objects and advantages of the invention, will become apparent from a study of the following specification, taken in connection with the accompanying drawings wherein like characters of reference designate corresponding parts throughout the several views, and wherein:

Figure 1 is a view in vertical section through a holding jig constructed in accordance with the present invention, showing the device in use.

Figure 2 is a front elevational view, showing the device mounted on the face plate of a grinding machine.

Figure 3 is a view in rear elevation of the device.

Figure 4 is a fragmentary view in vertical section, showing a tap reversed in the jig.

Figure 5 is a view in transverse section through the device.

Figure 6 is a perspective view of the device, showing certain of the parts separated.

Figure 7 is a detail view in perspective of the disc which accommodates the body portion of the tap.

Referring now to the drawings in detail, it will be seen that the embodiment of the invention which has been illustrated comprises a circular plate 1 of suitable metal. Openings 2 adjacent the periphery of the plate 1 accommodate screws 3 for firmly securing said plate in position on the face plate 4 of a grinding ma-

chine. The plate 1 is further provided with a comparatively large, centrally located, circular opening 5 which accommodates the usual head center 6 of the machine.

Mounted coaxially on the plate 1 is a metallic sleeve 7. Adjacent the opening 5, the plate 1 is apertured to accommodate countersunk screws 8 which secure the sleeve 7 in position on said plate.

10 Mounted for longitudinal sliding adjustment in the sleeve 7 is a metallic bushing 9 having a longitudinal groove 10 therein. The groove 10 is for the reception of a set screw 11 for securing the bushing 9 in adjusted position in the sleeve 7.

15 The outer end portion of the bushing 9 is counterbored, as at 12, for the reception of a removable disc 13. The disc 13 has formed in its periphery a notch 14 for the reception of a set screw 15 for releasably securing said disc in the adjustable bushing 9. The disc 13 is further provided with a square, centrally located opening 16 for the reception of the usual square end portion or head 17 of a tap 18 to be ground. The tap 18 is mounted between the head center 6 and the tailstock center 19 of the grinding machine.

20 It is thought that the operation of the device as thus far described will be readily apparent from a consideration of the foregoing. Briefly, the disc 13 is mounted in the bushing 9 and secured by the set screw 15. The bushing 9 is mounted in the sleeve 7 and secured in adjusted position by the set screw 11. The square end portion or head 17 of the tap 18 is engaged in

25 the opening 16 in the disc 13 and supported between the centers 6 and 19 of the machine. With the machine in operation, the set screw 15 positively secures the disc 13 to the bushing 9 for rotation therewith and the set screw 11 functions in a similar manner on the bushing 9. Thus, slipping of the tap is prevented and the body 20 thereof may be ground.

30 To grind the shank 21 of the tap 18, said tap is reversed between the centers 6 and 19 of the machine. To accomplish this, the disc 13 is removed and a disc 22 is substituted therefor. The disc 22 is provided with a centrally located opening 23 which is formed to accommodate or conform to the cross sectional shape of the body 20 of the tap 18. Thus, the tap 18 is again positively secured against slipping. The disc 22 is provided with a peripheral notch 24 which receives the set screw 15.

35 It is believed that the many advantages of a holding jig constructed in accordance with the

present invention will be readily understood, and although a preferred embodiment of the device is as illustrated and described, it is to be understood that changes in the details of construction may be resorted to which will fall within the scope of the invention as claimed.

What is claimed is:

A holding jig comprising a sleeve, means for mounting said sleeve on the face plate of a machine in spaced, concentric relation to the head center thereof, a bushing mounted for longitudinal sliding adjustment in the sleeve, said bushing having a longitudinal groove in its periphery, a set screw threadedly mounted in the sleeve and

engaged in the groove for securing the bushing in adjusted position in said sleeve, said bushing having a counterbored end portion, a disc removably mounted in said counterbored end portion of the bushing, said disc having a centrally located, non-circular opening therein for the reception of a correspondingly shaped end portion of a tool to be treated, said disc further having a notch in its periphery, and a set screw threadedly mounted in the bushing and engaged in the notch for releasably securing the disc fixedly in said bushing.

GEORGE ST. MARIE.
